United States Patent Office

Des. 205,331
Patented July 19, 1966

205,331

SANDWICH TOASTER

Fay J. Sawaya, 4299 Vallejo Drive,
Salt Lake City, Utah

Filed May 5, 1965, Ser. No. 85,122

Term of patent 14 years

(Cl. D81—10)

FIG. 1

FIG. 1 is a front perspective view of a sandwich toaster, showing my new design;

FIG. 2 is a side elevational view;

FIG. 3 is a plan view; and

FIG. 4 is a rear view.

The dominant features of my design reside in the portions shown in full lines.

I claim:

The ornamental design for a sandwich toaster, substantially as shown and described.
